(57) **CLAIM**

The ornamental design for an electricity measuring instrument, as shown and described.

DESCRIPTION

FIG. 1 is a front side perspective view of an electricity measuring instrument.

FIG. 2 is a front side view of the electricity measuring instrument.

FIG. 3 is a right side view of the electricity measuring instrument.

FIG. 4 is a top view of the electricity measuring instrument.

FIG. 5 is a left side view of the electricity measuring instrument.

FIG. 6 is a rear view of the electricity measuring instrument; and,

FIG. 7 is a bottom side view of the electricity measuring instrument.

The broken lines represent portions of the article that form no part of the claimed design.

1 Claim, 7 Drawing Sheets
